UNITED STATES PATENT OFFICE.

AXEL ELOF SPONGBERG, OF BROOKLYN, NEW YORK.

MECHANICAL TOY.

1,390,395.

Specification of Letters Patent. Patented Sept. 13, 1921.

Application filed November 2, 1920. Serial No. 421,225.

To all whom it may concern:

Be it known that I, AXEL ELOF SPONGBERG, a subject of king of Sweden, and a resident of #360 60th street, borough of Brooklyn, county of Kings, city and State of New York, have invented certain new and useful Improvements in Mechanical Toys, of which the following is a specification.

This invention relates to mechanical toys, and especially to that class wherein a jointed human figure may be caused to move with simultaneous rotation of a fan, by means of a spring motor, or by a breeze impinging upon the blades of said fan.

15 The purpose of this invention is to provide amusement at the expenditure of but little energy, this result being attained by the plurality of operative means mentioned.

Further advantages will become apparent 20 as this specification proceeds.

Referring to the drawing Figure 1 is a front view of an apparatus embodying the present invention.

Fig. 2 is a side view of Fig. 1.

25 In amusement devices of the character herein described, it is desirable to combine simplicity operation with maximum amusement.

My device is made by mounting upon a 30 base 1 a pair of flat duplicate pieces 2, 2 of wood or any other suitable material, to serve as legs for a human figure. A flat piece 4 serves as trunk and head of the figure, and is movably supported on the legs 35 by a pin 7.

Mounted on the same base with the figure is a casing 10, adapted to contain a suitable spring motor, which may be wound by a crank 16. To a smaller crank 5 at the front 40 of the casing is attached a pair of duplicate piece 6, 6 which serve as arms, being retained by the flat heads of pin 9. At their upper extremities, the arms are joined to part 4 by a pin 3.

45 It will now be apparent that any movement of crank 5 would be transmitted to the arms and trunk of the figure, so that the latter would assume a variety of successive postures, owing to its jointed construction.

50 However, in addition to the man's figure, a fan 12 is included with the toy, being mounted upon the post 15. The latter is really but an upward extension of motor casing 10, while the rear extremity of the 55 fan shaft is provided with a pulley 8. A

large pulley 14 is contained in the casing, and is mounted upon the shaft indicated in Fig. 2 by dotted lines, being the same shaft which bears the front crank 5. The crank and pulley 14 will thus move in unison upon 60 rotation of said shaft. This shaft and pulley are connected to the motor in any suitable manner, which detail it is aside from the purpose of the invention to illustrate. However, upon cranking the spring motor by 65 rear crank 16, the motor will cause crank 5 to rotate in a counter clockwise, so that, if the illustrated position of the figure be taken as the starting posture, three quarters of a revolution would bring the crank and 70 figure to the position indicated by the dotted lines at 11. The motor has been introduced to make the action of the figure more regular and effective, as well as more flexible, even though the rear crank be turned very 75 irregularly.

If a cord or belt 13 is used to connect pulleys 8 and 14, the rotation of the lower pulley will be transmitted to the fan, and the latter will thus rotate when the figure is in motion. 80 It may be noted that the fan itself could be used to drive the apparatus if it were placed in the path of a strong breeze, and the motor be made superfluous. If the motor were omitted, my invention would still be intact 85 and would operate satisfactorily by having the rear crank mounted directly upon the same shaft with the front crank. It is obvious that the casing 10 is merely a protective covering for interior parts according 90 to well known practice, and may be considered as simply an optional elaboration of post 15 at its lower part. There are therefore three general ways of causing my apparatus to operate, any or all of which may be used, 95 according to the desire of the person to be amused.

Having thus fully described my invention, I claim,

1. A toy including a jointed figure whose 100 parts are adapted to move in parallel planes, a base supporting said figure, a post upon said base having a rotatable crank mounted therein, a pin connecting the free end of said crank to the upper pair of movable extremities of said figure, and means for rotating said crank, with means for transmitting said movement to other parts of said toy including primarily a manually operated crank secured axially to said first crank behind said 105 110

post, and secondarily a pulley secured on the axis of said cranks connected by a cord to said other toy parts.

2. A toy including a movable figure consisting of jointed parts permitting movements in parallel planes, a base for said figure having a casing upon the same and a crank mounted in said casing, a pin passing through the free extremity of said crank and 10 through the upper pair of extremities of said figure, an extension upon said casing, a shaft mounted in said extension and provided with a multiblade fan on one extremity and a pulley

upon the other, a pulley upon the axis of said crank, a belt connecting said pulleys 15 and means for rotating said fan and moving said figure including a manually operated crank connected axially to said first crank.

Signed at 132 Nassau street, in the borough of Manhattan, county of New York, city and 20 State of New York this 30th day of October, 1920.

AXEL ELOF SPONGBERG.
